UNITED STATES PATENT OFFICE.

JOSEPH SOMORA, OF CHICAGO, ILLINOIS.

COMBINATION KEYLESS NIGHT LATCH.

1,417,777.

Specification of Letters Patent. Patented May 30, 1922.

Application filed July 11, 1921. Serial No. 483,841.

To all whom it may concern:

Be it known that I, JOSEPH SOMORA, a citizen of the United States, and a resident of Chicago, in the county of Cook and State 5 of Illinois, have invented a new and useful Improvement in Combination Keyless Night Latches, of which the following is a full, clear, and exact description.

My invention relates to combination controlled locking devices of the type of construction disclosed by me in my prior application on account of which Patent No. 1,380,260, was issued to me May 31, 1921, and it consists in the combinations, constructions and arrangements herein described and claimed.

An object of my invention is to provide a combination locking device that is adapted to be applied to a door and operatively connected with the spindle of a door lock of ordinary construction, whereby the door lock cannot be operated by persons not having the requisite knowledge as to the combination controlling the operation of the device.

A further object of my invention is to provide a device of the character described that is "keyless" and consequently more difficult of operation by unauthorized persons than is ordinary in night latches of ordinary construction.

A further object of my invention is to provide a device of the character described that is adapted to be attached to the outer side of a door by bolts projected through the door into engagement therewith from the inner side of the door, whereby the device cannot be readily removed from the door by any one seeking to open the door from the outer side.

Other objects and advantages will appear in the following specification, and the novel features of the invention will be particularly pointed out in the appended claims.

My invention is illustrated in the accompanying drawings forming part of this application, in which—

Figure 1 is a view in elevation of the outer side of a fragmentary portion of a door equipped with my invention,

Figure 2 is a section along the line 2—2 of Figure 1,

Figure 3 is a view similar to Figure 1, showing a fragmentary portion of the inner side of the door,

Figure 4 is an enlarged view in elevation of the inner or reverse side of the latch,

Figure 5 is a view similar to Figure 4 of the outer or obverse side of a portion of the latch,

Figure 6 is a view similar to Figure 5 of another portion of the latch,

Figure 7 is a section along the line 7—7 of Figure 4,

Figure 8 is an enlarged section along the line 8—8 of Figure 1, and

Figure 9 is a section along the line 9—9 of Figure 5.

Referring now to the drawings, 1 denotes a door, to the inner side of which is attached 70 a lock 2. The lock 2 is of any known type of construction in which a spindle 3 controlling the operation of a lock bolt 4 is projected through an opening in the door, such as indicated at 5, for connection with lock 75 bolt operating means attached to the outer side of the door.

A casing 6 is provided with a front or outer wall 7, side walls 8 and 9 and end walls 10 and 11, being open at its inner or 80 rear side. The casing 6 is attached to the outer side of the door 1 by means of bolts 12 which are projected through the door from the inner side thereof into engagement with threaded openings in the inner faces 85 of the end walls 10 and 11. The spindle 3 is arranged to enter a slot 13 in the inner end of a shaft or stud 14. The latter is journalled in the front wall of the casing 6 and is provided with a knob or handle 15 at its 90 outer end. A pinion 16 is rigidly mounted on the stud 14 to lie flat against the inner wall of the front side 7 and is in mesh with rack portions 17 and 18 of tumbler plates 19 and 20 respectively. The latter are parallel with one another and corresponding end portions thereof are slidable in guideways 21 and 22, respectively, as shown in Figure 6. It will be observed that the guideways 21 and 22 extend transversely of a 100 guide plate 23 that is secured to the inner face of the front wall 7 by means of screws 24. A compression spring 25 having an end seated in the rack 17 tends to move the plate 19 in one direction, while a similar compression spring 26 seated in the rack 18 tends to move the tumbler plate 20 in the opposite direction. A U-shaped retaining plate 27 is secured to a boss 28 projecting inwardly 105 from the inner face of the front wall 7 and 110

holds the tumbler plates 19 and 20 against displacement.

A slideable plate 29 has a reduced end portion 30 arranged to protrude through an opening 31 in the side 9 and is held against displacement by oppositely extending integral tongues 32-32' which are arranged to enter grooves 33-33' in the guide plate 23 and in an enlargement or boss 34 that is integral with the front wall 7. The tongue 32 is cut away adjacent to the opening 31, as at 35, to receive the end of the tumbler plate 19, and is also provided with a slot 36 adjacent to its other end, into which slot, a relatively reduced end portion 37 of the tumbler plate 20 projects at times. The slideable plate 30 is formed with a plurality of laterally projecting alined lugs 38, 39, 40, 41 and 42, these lugs being spaced apart to provide guideways 43, 44, 45 and 46 for a purpose which will be hereinafter set forth.

A rear cover plate 47 has the form best seen in Figure 5 and is attached to the front wall of the casing by screws 48 or like fastening means. The rear cover plate 47 depends below the lower end of the casing and terminates approximately midway the length of the latter. The face of the cover plate 47 contiguous to the inner side of the front wall 7 is formed to provide a transverse channel 49 adapted to receive the end wall 11, and with parallel grooves 50, 51 and 52 which extend from the channel 49 to the upper end of the plate. The grooves 50, 51 and 52 are intersected by a transverse groove 53. Combination plates 54, 55 and 56 are slidably disposed in parallelism in a recess 57 in the cover plate 47 and have relatively reduced portions arranged to enter the grooves or guideways 50, 51 and 52, as best seen in Figure 5. The combination plates are bent laterally at their lower ends, as at 54^a, 55^a and 56^a to provide means adapted to be grasped when it is desired to slidably move the combination plates. The plates 54, 55 and 56, respectively, have extensions 54^b, 55^b and 56^b arranged to project through slots 54^c, 55^c and 56^c in the cover plate 47, these extensions being upset at their ends to prevent displacement of the combination plates. Each of the combination plates is provided with a slot in its face contiguous to the inner side of the wall 7, as indicated at 54^d, 55^d and 56^d. These slots or grooves may be moved in alinement with one another and with the transversely extending groove 53 when the combination plates are moved in accordance with a predetermined plan. It will be observed that each of the combination plates is provided with a series of graduations on the portion thereof projecting below the lower end of the casing 6, as indicated generally at 54^e, 55^e and 56^e. The outer face of the front wall 7 is beveled, as 65 at 58, (see Figure 1) to provide a sharp in-

dex edge adapted to indicate on the scales marked on the combination plates the relative positions of the several combination plates.

In order to make the opening of the device more difficult than is usual in combination locks, I provide additional or secondary combination controlled means indicated generally at 59 and 60. The member 59 comprises parallel spring arms 61 and 62 arranged to straddle the combination plate 56 and being slideable in the groove or channel 52. The arms 61 and 62 are connected at their upper ends by an arm of a U-shaped member 63. The combination controlled member 60 likewise comprises parallel spring arms 64 and 65 arranged to straddle the combination plate 54 and connected at their upper ends by an arm of a U-shaped member 66. The arms of the U-shaped members 63 and 66 are arranged to be engaged successively and selectively by the cross bar 67 of an actuating member having a stem 68 secured to the combination plate 55.

From the foregoing description of the various parts of the device, the operation thereof may be readily understood. When the latching device is secured to the outer side of the door 1 by means of the bolts 12, and the spindle 3 is secured in the slot 13 in the end of the stud 14, as by means of a cotter pin 69, it is obvious that the latch cannot be readily removed from the door by anyone seeking to open the door from the outer side. When the combination plates 54, 55 and 56 have been moved in accordance with a predetermined plan, as indicated by the registration successively of certain graduations on the scales 54^e, 55^e and 56^e with the index edge 58, the transverse grooves 54^d, 55^d and 56^d will be alined with the guideway 53. At this time alined notches 64^a and 65^a in the arms of the combination controlled member 60 will be in alinement with the groove 53 and notches 61^a and 62^a in the arms of the combination controlled member 59 will likewise be in alinement with the same groove. A slight rotative movement of the knob 15 will now occasion the retraction of the end of the tumbler plate 19 from the recess 35 and the slideable plate 30 can be moved laterally of the casing 6, since the lugs 38, 39, 40, 41 and 42 will be disposed in the alined transverse grooves. When the slideable member 30 has been moved laterally, the knob 15 may be rotated at will to occasion the retraction of the lock bolt 4. The slideable plate 30 is preferably formed with a lateral extension 70 that protrudes exteriorly of the casing 6 and provides a convenient means for manipulating the same. Springs, such as indicated at 71, react against the sides of the combination plates contiguous to the cover plate 47 and tend to maintain the combina-

tion plates in frictional contact with the guide plate 23 and the boss 34.

I claim:

1. In a device of the type described, a casing, a plurality of manually controlled combination plates carried by said casing, said plates having grooves adapted to be alined with each other, a lock plate having a plurality of alined lugs adapted to be received in the grooves when the grooves are alined, a shaft having a pinion rigidly secured thereto, a pair of slideable racks constantly in mesh with said pinion, said racks engaging with said lock plate and preventing the rotation of said shaft, when the lugs in said plate are out of engagement with said grooves, said racks being free to move when said lugs are received in said grooves.
2. In a device of the type described, a casing, a plurality of manually controlled combination plates, each plate having a groove therein, said plates adapted to be moved so as to aline the grooves in said plates with each other, a plurality of members having grooves therein adapted to be brought into alinement with said first named grooves, said members adapted to be moved by one of said plates, and a locking plate having a plurality of alined lugs adapted to be received in the grooves in said plates and members when said grooves are alined.

3. A device of the type described comprising a casing, a plurality of manually controlled combination plates, each of said plates having a groove therein, said casing having a groove therein, said plates adapted to be moved to aline the grooves in said plates with the groove in said casing, a plurality of members, each having a groove therein, one of said plates being adapted to move said members so as to aline the grooves in said members with the groove in said casing, and a locking plate having a plurality of alined lugs slidably disposed in the groove in said casing, said locking plate being movable when the grooves in said combination plates and said members are alined with the groove in said casing.

4. A device of the type described comprising a casing, a plurality of manually controlled combination plates, each of said plates having a groove therein, said casing

having a groove therein, said plates adapted to be moved to aline the grooves in said plates with the groove in said casing, a plurality of members, each having a groove therein, one of said plates being adapted to move said members so as to aline the grooves in said members with the groove in said casing, a locking plate having a plurality of alined lugs slidably disposed in the groove in said casing, said locking plate being movable when the grooves in said combination plates and said members are alined with the groove in said casing, a shaft rotatably carried by said casing, a pinion rigidly secured to said shaft, and a pair of racks held in constant engagement with said pinion and abutting said locking plate, said racks permitting the rotation of said shaft when said locking plate is moved so that the lugs are received in the grooves of said combination plates and members.

5. A device of the character described comprising a casing, a shaft journalled in the casing and adapted to operatively engage a lock spindle, a knob secured on the portion of the shaft protruding from the casing, a pinion rigidly mounted on the shaft within the casing, a pair of slideable racks arranged to constantly engage the pinion at diametrically opposed points, said racks being reduced adjacent to corresponding ends to provide similar tumbler plates, a transversely arranged plate slidably disposed in the casing and formed with recesses in one side adapted to receive the ends of the tumbler plates when the slideable transverse plate is in a certain position, said slideable transverse plate being formed with a plurality of alined integral lugs projecting from a face thereof, and a plurality of slideable combination plates arranged for slideable movement across the face of the slideable transverse plate and each being provided with a notch in its face contiguous to the slideable transverse plate, said notches being adapted to be moved into registry and into position to receive the lugs on the slideable transverse plate when the combination plates are relatively arranged in accordance with a predetermined plan.

JOSEPH SOMORA.
